United States Patent Office.

JOHN GREENWALD, OF CINCINNATI, OHIO.

Letters Patent No. 72,193, dated December 17, 1867.

IMPROVED MEDICAL COMPOUND.

The Schedule referred to in these Letters Patent and making part of the same.

TO ALL WHOM IT MAY CONCERN:

Be it known that I, JOHN GREENWALD, of Cincinnati, Hamilton county, and State of Ohio, have invented a new and improved Compound—a Cathartic for Medicinal Purposes; and I do hereby declare the following to be a full and clear description of the same, reference being had to the accompanying sample.

My invention relates to a new compound to entirely supplant castor-oil in all the various purposes to which it has heretofore been applied medicinally.

Take ten grains of compound extract of colocynth, dissolved in six fluid drachms of glycerine, to which must be added two fluid drachms of some flavoring-sirups.

The advantages over castor-oil are that it acts with equal kindness, and but half the quantity for the desired effect is required. It acts with more certainty, and is comparatively very palatable.

Having thus described my invention, what I claim, and desire to secure by Letters Patent, is—

The compound as specified, for the purposes set forth.

JOHN GREENWALD.

Witnesses:

I. J. MILLER,

P. KILLIN.
